UNITED STATES PATENT OFFICE

MORTON K. MOORE, OF CHARLESTON, SOUTH CAROLINA

GRATE

Application filed November 28, 1927. Serial No. 236,219.

My invention relates to grates, and more particularly to improvements in the grate bar disclosed in the co-pending application of Henry K. Milner, for grate, filed June 14, 5 1926, Serial No. 115,928, and which application was assigned to me August 24, 1927.

An object of the present invention is to generally improve the interchangeable grate elements disclosed in the above identified application.

The invention further provides a grate element or unit which is so constructed as to prevent the accumulation of hot coals and the resultant burning out of the grate elements 15 or units.

Further the invention contemplates a grate element wherein a maximum natural draught will be conducted thereto, and thus keep the grate element in a maximum cool state.

With the preceding and other objects and advantages in mind, the invention consists in the combination of elements, construction, arrangement of parts and operations to be hereinafter specifically referred to, claimed 20 and illustrated in the accompanying drawings, wherein:

Figure 1 is a fragmentary horizontal sectional view of a fire box having grate bars made up from my improved replaceable grate 30 element or unit;

Figure 2 is a front elevation of my improved grate element received in its supporting bar, the supporting bar being shown in vertical cross section;

Figure 3 is a vertical sectional view taken on line 3—3 of Figure 2;

Figure 4 is a horizontal section on line 4—4 of Figure 2;

Figure 5 is a side elevation of a modified 40 embodiment of the invention.

Figure 6 is a vertical section taken on line 6—6 of Figure 5; and

Figure 7 is a fragmentary perspective of the supporting bar embodied in the invention.

Referring to the invention in detail, a hollow rectangular supporting bar 5 having vertical rectangular cells or sockets 6 is provided.

My improved grate element or unit com-

prises a longitudinally curved segment 3 cast with lateral enlargements 10 substantially triangular in vertical cross section. These enlargements 10 are of greater width than the transverse width of the segments 55 and are formed with a V-shaped seat 11 at one end, and a V-shaped tongue 12 at its opposite end which interfits in the V-shaped seat 11 in the enlargement of the adjacent element. As illustrated in Figure 1, the seats 11 and tongues 12 of the enlargements of each grate element or unit are disposed reversely so that all of the grate elements interfit and retain the grate in assembled relation to afford a fire bed or grate surface. Due to the arrangement of the seats and tongues, the grate elements or sections can only be assembled in 60 mating relation. In order that the grate bars may be rocked to dump or clear the same, the opposite ends of the enlargements 10 are beveled as indicated at 9.

Formed integrally with the segment 3 and arranged directly below the slots or ventilating openings 13 therein is a pair of oppositely arranged curved arms 14 whose outer ends 75 merge into the underface of the enlargements and ends of the segment. These arms have their upper edges 15 beveled to cause dropping coals or ashes to fall therefrom, and thereby prevent accumulation of hot coals 80 or ashes which ordinarily would burn out or destroy the grate element.

A central vertical brace 16 integrally connects the under face of the segment and the arms 14 which, in addition to reinforcing the 85 grate element, also serves to support the segment in the event that the latter becomes cracked or broken at one or both sides of the brace.

A vertically disposed shank 17 rectangular in cross section is connected with the arms 14 in vertical alinement with the brace 16, and is adapted to be received in one of the rectangular sockets or cells 6 in the supporting member 5. With the shank thus positioned the segment 3 extends transversely of the member 5 above the latter. Vertical grooves 18 extend the entire length of the opposed faces of the shank, and constitute air passages which communicate at their 90 95 100

upper end with lateral outlet openings 19 to supply air currents to the arms 14 and adjacent parts for cooling purposes.

This construction produces a clear airway 5 to the grate elements and fuel, thereby giving a maximum life to the grate elements and causes more perfect combustion of the fuel.

To prevent accumulation of burning coals 10 or ashes between adjacent grate elements, inverted V-shaped shields or deflectors 20 are disposed upon opposite sides of the arms and brace 16 directly above the air passage ways. These shields or deflectors project 15 laterally and are positioned with their apexes disposed at the vertical center of the brace 16 and their ends projecting beyond the openings 19. As illustrated in Figure 1, the shields or deflectors of the adjacent grate 20 elements abut to entirely close the space between the grate elements above the member 5. It will be observed that any coals or 25 ashes dropping between the grate elements will be deflected laterally beyond the opposite vertical faces of the member 5 so that they will fall directly into the ash pit below. In this connection, it will be observed that the lower edges of the shields or deflectors extend slightly beyond the member 5.

In Figures 5 and 6, I have illustrated my 30 improvement with a modified form of grate element. In this instance a flat bar 21 is formed at the upper end of a vertically extending web 22 from which the shank 17 35 extends. In this instance the deflectors or shields 20 are cast on the opposite faces of the web directly above the shank. The bar 21 is of greater cross sectional area than the web, and the under face of the bar is bevelled 40 upon opposite sides of the web as at 23 to direct air currents along the bar to prevent burning out of the latter. To further aid in the cooling of the grate element, the web is provided with ventilating openings 24. If 45 desirable the bevels 23 may be substituted by square corners.

What is claimed is:

In a grate element, a fuel supporting member, a shank extending from the under side 50 of the fuel supporting member and located centrally of the extremities of the latter, an inverted V-shaped member projecting laterally from one face of the fuel supporting member above the shank and having its ends projecting downwardly beyond opposite 55 sides of the shank, the shank having a longitudinally extending air passage throughout its entire length and laterally extending air passages at its upper end which open on opposite faces of the shank at points adjacent the lower ends of the inverted V-shaped 60 member.

Signed at city of Washington, in the District of Columbia, this fourth day of November, 1927.

MORTON K. MOORE.
